INVENTOR:

Richard Cooke Fogg
BY Wright & Dunn Linby May
ATTYS.

UNITED STATES PATENT OFFICE.

RICHARD COOKE FOGG, OF BOLTON, ENGLAND, ASSIGNOR TO WILLIAM WALKER AND SONS LIMITED, OF BOLTON, ENGLAND.

APPARATUS FOR STRETCHING LEATHER.

Application filed January 20, 1925, Serial No. 3,555, and in Great Britain January 26, 1924.

In the stretching of leather when in the full hide or in sides or butts, it is desirable that even tension should be put thereon so that said leather is brought into a flat, straight and even condition and that without causing any damaged parts thereon, to attain this object according to my present invention I follow such a method and make use of such means as enable the leather to be held against becoming narrower in width while it is being stretched lengthwise, thus when the stretched leather is dried it is even and flat, being entirely free from undulations, creases or other markings which result from the method of stretching heretofore followed. I am further enabled to arrange the different stages of preparing, stretching and drying to be carried out by different workmen in order to keep the process continuous from the taking of the hides in their soft, moist condition, placing each hide within framework, applying gripping devices to the edges of said hides in suitable and appropriate positions thereon, handling such frame work in order to place same in apparatus for pulling or exerting strains thereon for distending the hides lengthwise (in manner before stated), removing the framework and its hide and carrying same along run-ways or trolley rails which take them into positions where they remain until dried or are carried slowly along a path that may occupy such time as will enable said drying to be effected before the framework and hide are taken forward to have the said hide detached ready for other hides of leather to be mounted therein to repeat the operation.

To enable my method and the means which I employ for carrying same into effect to be clearly understood, I have hereunto appended sheets of drawings illustrative thereof, to which by figures and letters reference is made in the following description.

Figure 1 is a plan view of my improved leather stretching apparatus.

Figure 2 is a view of the stretching frame suspended for transfer from one table to another.

Figure 3 is a side elevation of the frame resting on a table.

Figure 4 is a detail showing in elevation one of the side clamps attached to the stretching frame.

Figure 5 is a plan view of a portion of Figure 4.

Figure 6 is a fragmentary perspective of one of the end members of the frame.

Figure 7 is a section on the line A—B of Figure 2.

Figure 8 is a side elevation of one of the end clamps showing its manner of engagement with the end member illustrated in Figure 6.

Figure 9 is a detail of one corner of the frame shown in Figure 2, indicating how one part may be adjusted on another.

Figure 10 is a sectional end elevation of the parts shown by Figure 9.

The method of stretching the hides which I follow in accordance with my invention is carried out by gripping each of the edges at the two sides of the hide by jaws which may put slight tension on the whole hide in a lateral direction. One end of the hide is also laid hold of by a jaw which extends from edge to edge of the hide as is herein-after explained while the other end of the hide is laid hold of by a series of jaws occupying irregular positions according to the irregular shape of that end of the hide, and these latter jaws are mounted upon an operating member which will cause them to stretch or distend the hide lengthwise. When these jaws are thus stretching the hide the jaws which engage the sides of same are permitted to move as the stretching of the hide along the parts which support them carries them forward, by which arrangement the stretching is effected without the hide being in any way engaged with except at its extreme edges all around it thus by being stretched longitudinally while it is held against being made narrower during said stretching operations all creases and undulations are entirely avoided and the leather when dried is flat and even throughout its whole area.

The means which I employ for engaging with each hide A, are most clearly illustrated by Figures 1, 2 and 3 of the drawings which show a rectangular frame 3 formed by the bars a, b, c and d.

The bars b and d are fixed to the cross bar a which cross bar a is constructed or formed as is herein-after fully explained while the cross bar c is arranged to slide over the longitudinal bars b and d at one

time, and at another time this cross bar *c* may be fixed to said bars *b* and *d* by means of the screws 4.

The construction of the joints with the bolts 4 is shown in detail by Figs. 9 and 10 of the drawings.

The frame 3 (formed of the bars *a* *b* *c* and *d*) is of rectangular formation to enable me to fix a cross bar gripping jaw 5 to the bar *c* at one end and a series of separate gripping jaws 6 upon the bar *a* at the other end.

The cross bar 5 is in the form of a gripping jaw (shown by Fig. 10) so that by the screws 7 said bar 5 may grip the edge of 15 the hide of leather A as shown by Figs. 7 and 10 and in broken lines by Fig. 2.

The separate or independent gripping jaws 6 which are caused to grip by tightening nuts 8^a on the bolts 8 are mounted upon 20 the bar *a* by said bolts taking through slots *w* made in said bar *a* as is shown by Figs. 1, 7 and 8, thus the series of gripping jaws 6 may be mounted in the irregular positions shown by Fig. 2 where they are adjusted 25 to take hold of the irregular edge of the hide A as shown by said Fig. 2.

The cross bar *a* is formed of box-shape as is shown by the end views of same in Figs. 7 and 8 and in perspective by Fig. 6.

30 I employ this formation because it affords facilities for retaining the bolts 8 (which cause the jaws 6 to grip) to retain their positions in the slots when their nuts 8^a are loosened to relieve their gripping 35 actions since in this case the bolts 8 merely descend for their heads to rest upon the opposite wall (or, when the frame 3 occupies its horizontal position, the base) of the rail *a*, thus their extending ends remain in position ready for the workmen to again cause 40 the jaws 6 to grip when another hide has been placed in position. The heads of bolts 8 are permitted to pass into the grooves *w*¹ (see Fig. 6) of the rail *a* when the body 45 parts of said bolts are passed through the ends of the slots *w*, while when thus placed said bodies of the bolts may be slid along the slots *w* as their adjustment necessitates. This sliding of the bolts 8 is permitted by 50 notches *w*² being formed in the upturned edge of the rail *a* for the heads of the bolts to pass through (see Fig. 6). As the bar *a* may be of metal that might stain or mark the leather, we prevent this by fixing strips 55 of wood *p* on the upper face thereof to prevent contact of the leather with the said face of the bar *a*.

The single gripping jaw 5 mounted on the rail *c* and reaching from side to side 60 along the opposite end of the hide A, acts as a single gripping jaw as above described.

Along the two sides of the hide A are mounted other gripping jaws 9 of the formation illustrated by Figs. 4 and 5 and these are caused to grip by bolts 10. These

are arranged along the edges of the hide A by being mounted on screws 11 which take through brackets 12 which are arranged to slide along the flanges *x* of the side rails *b* and *d* as shown by Fig. 4.

When the hide in its moist condition is fixed within the frame 3 and all of the series of gripping jaws (shown by Fig. 2) engaging the edges surrounding the hide A, are secured with the jaws 9 on each of the side bars *b* *d* moved laterally as far as may be by the workmen operating the winged nuts 11^a on the screws 11, the whole frame 3 is raised by appropriate hoisting devices hereinafter explained and carried from the 70 table 2 or 2^a to be placed upon a stretching table 13.

Mounted upon the longitudinal beds *s*, *s*¹ which form part of this stretching table 13 are two screws 14 and 14^a which take into 75 screwed brackets 13^a, 13^b carried by a sliding rail 15. This rail 15 is mounted to slide over the bed of the table 13 as it is operated by its screws 14 and 14^a.

These screws 14, 14^a are rotated through 80 the medium of the gearing wheels 14^b and 14^c respectively and said wheels are fixed upon said screws in order to mesh with and derive their motion from a central pinion 16.

This pinion 16 derives its motion through a driving chain 17 which operates a sprocket wheel 17^a fixed upon the hub of the said pinion 16. The chain 17 also takes around a sprocket wheel 18 which is fixed upon a shaft 19 upon which is fixed another sprocket wheel 20. This wheel 20 has its chain 21 to encircle a sprocket wheel 22 fixed upon the shaft 23 of an electric motor 24, and said motor is provided with means of well known 90 character whereby its direction of rotation may be reversed as and when desired.

Although I state that I use an electric motor, it is obvious that I may transmit motion to the screws 14, 14^a from any prime 95 motor, but as an electric motor affords facilities for ready reversal of its actions I preferably employ same.

The rectangular frame 3 is pivoted (approximately mid-way its length and at each side) to a spanning member 25 which engages the lateral studs 26 that extend from the bars *b* and *d* of said rectangular frame 3 so that these will swivel in openings on the extending ends of said spanning member 25 in order that when the frame 3 with its hide is placed horizontally upon the table 2 or 2^a this member 25 may still retain its pendent position which permits the workmen to place the frame 3 upon the table 2 or 2^a and carry out the fixing of the hide therein by the series of gripping jaws hereinbefore described.

The process carried out by the apparatus hereinbefore described commences with the 100

workmen placing a frame 3 upon one or other of the tables 2 or 2^a.

The hide in its moist condition is taken and one edge near the shoulder of the hide 5 (which is of irregular formation as is shown by Figs. 1 and 2) is arranged to be gripped close to the edges by the adjustable grippers 6. The slots in the cross rail *a* enabling the adjustment of said grippers 6 as 10 is hereinbefore explained.

The grippers 9 which are arranged on the bars *b* *d* along the two sides of the hide A are then brought into use and are caused to grip the hide close to its edges and these 15 grippers are then drawn laterally from said hide by their screws 11 being acted upon by the winged nuts 11^a (see Fig. 2) while the guiding brackets 12 lie loosely upon the two guiding rails *b* and *d*.

20 The other end of the hide is gripped by the longitudinal gripping jaw 5 which is in the form of a rail fitted with a strip of incorrodible metal which will not mark or stain the hide and this gripping rail 5 is caused to grip by the tightening up of the 25 screws 7.

The hide and frame are then transferred to a stretching apparatus as shown in Figure 1.

30 On the stretching apparatus being put into action to cause the bar *c* to slide upon the bars *b* and *d* when the desired stretch has been carried out (as indicated by graduations on the bar *b* or *d*) the binding 35 screws 4 are tightened up to grip the side bars *b* and *d* there to hold the cross bar *c* in position.

Such being the nature and object of my 40 said invention what I claim is:—

1. In apparatus for stretching leather, a frame having side bars and transverse members, one of said transverse members being movable toward and from the other, gripping means on said transverse members, 45 means engaging said transverse members and actuatable to move said members relatively to stretch the leather longitudinally

of the frame, and means slidably mounted on each of the side bars for gripping the sides of the leather, said means being actuatable to stretch the leather laterally at any stage of the process of stretching longitudinally.

2. In apparatus for stretching leather, a frame having side bars and transverse members, means cooperating with the transverse members to stretch the leather longitudinally of the frame, and means slidably mounted on said side bars for gripping the side edges of the leather at spaced points, 55 said gripping means on one of the side bars being actuatable to cooperate with the gripping means on the opposite side bar to stretch the leather laterally at any stage of the longitudinal stretching operation.

3. In a frame for stretching leather, an end bar formed of sheet metal bent into a hollow form having spaced side portions, one of said side portions having slots extending laterally of the bar, headed bolts disposed through said slots having their heads within said hollow, jaws and nuts on said bolts and strips of protective material mounted on said bar between said slots.

4. In a frame for stretching leather, a 75 hollow and relatively wide metal end bar comprising spaced upper and lower face portions, an edge portion integral with said face portions, and a flange integral with each face portion and substantially perpendicular thereto, the edge of the flange on said lower portion abutting the upper face portion and having notches formed therein, said upper face portion having slots therethrough extending laterally of the bar and 80 corresponding to said notches in combination with headed bolts disposed through said slots having their heads positioned between said face portions, gripping jaws and a nut on each bolt, and strips of protective 85 material secured to said upper face portion between said slots.

RICHARD COOKE FOGG.
